UNITED STATES PATENT OFFICE.

JOHN CLARK, OF WALKERTON, INDIANA.

TRACK LINER.

Application filed May 3, 1924. Serial No. 710,844.

To all whom it may concern:

Be it known that I, JOHN CLARK, citizen of the United States, residing at Walkerton, in the county of St. Joseph and State of Indiana, have invented certain new and useful Improvements in Track Liners, of which the following is a specification.

The present invention relates to track liners or jacks.

10 An object of the invention is to provide an instrument for adjusting a rail laterally.

Another object of the invention is to provide a device which can be operated to accomplish the lifting and proper positioning of a track rail with a minimum of labor and effort.

Still another object is to provide a device for this purpose which shall have a 20 movable foot, by which shifting of the rail will be facilitated, and which will eliminate the necessity of providing prongs or other means on the base plate to prevent its slipping on the ballast and sliding out from 25 under the rail.

A further object of the invention is to provide such a device which is simple in construction and easy to operate, and in 30 which the effort of the operator is not wasted by unnecessary friction between the parts.

Still further objects and advantages of the invention will be apparent from the following description taken in connection with 35 the accompanying drawings, which illustrate a preferred embodiment of the invention, and in which:

Fig. 1 is a side elevation showing the operating lever in partly raised position;

40 Fig. 2 is a top plan view of Fig. 1;

Fig. 3 is a side elevation, partly in section, showing the operating arm in its lowered position.

Fig. 4 is a fragmentary side elevation, 45 partly in section, showing the movable foot of the operating lever.

Fig. 5 is a sectional elevation showing the movable foot of the operating lever, and taken on the line 5—5 of Fig. 2.

50 Referring in detail to the drawings, in which like reference numerals indicate like parts throughout, the embodiment of the invention here shown comprises a base plate 1, which may conveniently be of suitable metal 55 and rectangular in form, as shown.

Near one end of the base plate is located a mounting plate or movable foot 2, provided with lugs 3 through which a bolt 4 passes pivotally securing the operating lever 7 to the movable foot 2. The movable foot 2 is retained in sliding contact with the base plate 1 by any suitable means such as the side guide plates 5 and 5' secured to the base plate 1 by suitable means such as the screw bolts shown, and movement of the movable foot 2 forwardly and rearwardly on the base plate 1 may be limited by the stop bolts 6. The mounting plate 2 thus forms a movable or sliding foot for the operating lever 7.

The operating lever 7 may conveniently take the form illustrated in the drawings, and be provided at its free end with a socket 8, designed to receive a wooden or other lever, preferably several feet in length, to increase the length of the lever arm, and thereby facilitate the operation of the track liner. The track engaging lever is shown as being constructed of two side plates 9 and 10, spaced apart and embracing between them at one end the operating lever 7, to which the side plates 9 and 10 are pivotally attached by the pivot bolt 11. The top edges of these side plates form the track engaging portion of the liner.

The other ends of the track engaging lever are free, and carry between them the antifriction roller 12, mounted between said side plates on the bolt 13, upon which the roller 12 is freely rotatable. The diameter 80 of the roller is such, in relation to the side plates, that the bottom of the roller extends below the lowermost portion of the side plates and contacts with the top surface of the base plate, upon which it may roll when the track liner is being operated.

A strap or stop 14 may be secured to the base plate, for example, by the bolts 15, and include between its ends the roller 12, embracing said roller and passing over it 100 between the side plates 9 and 10. The strap 14 is shown as being, substantially, of inverted U-shape, and there is sufficient space between the arms of the U to permit considerable movement of the roller 12 back and forth on the base plate. The strap 14 also acts to prevent the track engaging lever from swinging away from the base plate, and thus makes the liner more compact and easier to transport.

In operation, the track liner is brought up to the rail on the side away from which it is to be moved, until the track engaging lever contacts with the rail. A wooden or other lever may then be conveniently inserted in the socket 8 and used to raise the operating lever 7 about its pivot on the mounting plate or movable foot 2. The effect of this will be to raise the track engaging lever and at the same time move it forwardly, the upper portion of the operating lever being moved forward with the rail, and the lower portion of the operating lever and the movable foot 2 sliding rearwardly on the base plate. The movable foot is so constructed that it has just enough surface bearing on the base plate to slide thereon when sufficient power is put on the operating lever before the base plate slips on the ballast, and thereby prevents the liner from slipping out from under the rail. The sliding of the movable foot on the base plate also makes it possible to use a smooth base plate, that is, one without any prongs or other means to prevent its slipping back on the ballast. The roller 12 eliminates friction between the track engaging lever and the base plate, and is prevented from moving off the base plate by the strap 14.

It will be seen that by the foregoing construction there has been provided a track liner by which the rails of a track may easily and quickly be shifted, and one which may readily be carried about and brought into position and be operated efficiently by a minimum of labor; and that the operating parts are all slidable on a smooth surface which forms a part of the track liner. It will also be observed that friction is decreased by lifting the rail as well as shifting it, and that due to the sliding movement of the movable foot, the base plate remains in a steady position on the ballast, no prongs or other means being needed to steady it.

What is claimed is:

1. A track liner comprising a base plate, an operating lever pivotally associated therewith and having a foot longitudinally slidable thereon, and a track engaging lever having one end pivoted to said operating

lever and having its other end movably associated with said base plate.

2. A track liner comprising a base plate, an operating lever, a movable foot for said operating lever longitudinally slidable on said base plate, said operating lever being pivoted to said movable foot, and a track engaging lever pivotally associated with said operating lever.

3. A track liner comprising a base plate, an operating lever pivotally associated therewith and having a lower portion longitudinally slidable with respect thereto, a track engaging lever having one end pivoted to said operating lever, and an antifriction roller carried by the other end of said track engaging lever and movable on said base plate.

4. A track liner comprising a base plate, a movable foot longitudinally slidable thereon an operating lever pivoted to said movable foot, and a track engaging lever comprising side plates embracing at one end said operating lever, and pivoted thereto, and having at its other end an antifriction roller movable on said base plate.

5. A track liner comprising a base plate, a movable foot longitudinally slidable on said base plate, an operating lever pivotally associated with said movable foot, a track engaging lever having one end pivoted to said operating lever and its other end movable on said base plate, and means for guiding said movable foot on said base plate and limiting its movement thereon.

6. A track liner comprising a base plate, a movable foot longitudinally slidable on said base plate, an operating lever pivotally associated with said movable foot, a track engaging lever having one end pivoted to said operating lever and an antifriction bearing roller at its other end movable on said base plate, means for limiting the movement of said movable foot on said base plate, and means for limiting the movement of said antifriction bearing roller on said base plate.

In testimony whereof I affix my signature.

JOHN CLARK.
